W. K. Meyer,
William L. Symons

Attorney

UNITED STATES PATENT OFFICE.

WILLIAM K. MEYER, OF NEW YORK, N. Y.

NECKTIE.

1,412,665.

Specification of Letters Patent. Patented Apr. 11, 1922.

Application filed June 29, 1921. Serial No. 481,244.

To all whom it may concern:

Be it known that I, WILLIAM K. MEYER, a citizen of the United States, residing at 2025 Broadway, New York city, in the 5 county of New York and State of New York, have invented certain new and useful Improvements in Neckties, of which the following is a specification.

My invention relates to the manufacture 10 of neckties, and especially to four-in-hand ties, which have a narrow neck band portion and wider end portions.

An object of my invention is the construction of a tie by which there is a saving of 15 the expensive material used in making the tie, without in any way affecting the strength, lasting qualities, or beauty of the tie.

A further object of my invention is to do 20 away with the ridge resulting from the seam extending the full length of the tie at the joining place of the back fold of the outer material of which the tie is made.

With these and further objects in view, 25 one embodiment of my invention is shown in the accompanying drawings, in which—

Figure 1 is a plan view of the back of the tie with certain parts broken away.

Figure 2 is an edge view thereof.

Figure 3 is a plan view of the front of the tie.

Figure 4 is a section on line 4^x—4^x of Figure 1.

Figure 5 is a section on line 5^x—5^x of Figure 1.

Figure 6 is a section on line 6^x—6^x of Figure 1.

The tie shown in the accompanying drawings consists of two pieces of silk 1 and 2 or 40 other suitable material folded as shown and joined by a bias seam 3. It has a suitable lining 4 extending from the point 5 to the point 6 from which points to the ends of the material the adjacent edges are free.

45 The outer material is cut away from both edges from point 7 to point 8 as clearly shown in Figures 1 and 5, the space between the edges of the outer material being designated by 9, in Figure 5. In order to attach 50 this material securely and to avoid the seam on the back of the tie a narrow strip 10 is inserted above the lining 4, and between the edges of the outer material, as clearly shown in Figures 1 and 5, to which it may

be stitched by hand. The usual band 11 of 55 any suitable closely woven material is then placed on top of this strip, and above the edges of the silk. This band may have a tab 12 at the end thereof to assist in placing the tie in position and tying it without 60 injuring the material of which the tie is made or tearing any of the parts thereof.

The strip 10 may be sewed by hand to the edges of the silk, as indicated at 13. The band 11 extending from point 14 to point 65 15 and over the cut away part of the silk outer material may then be machine stitched, the stitches extending through the band, the strip 10, the lining and the outer material from point 14 to point 16. From point 16 70 to point 15 the band is stitched by hand to the back fold of the outer material, the strip and the lining, the stitches not extending through the outer material, as shown in Figure 3.

75 The machine stitching is indicated by dotted longitudinal lines, and the hand stitching by lines at an angle thereto, as shown in Figure 1.

There will be no seam from point 8 to 80 point 7. The absence of this seam is a new feature in my tie which results in a thin, flat tie. This construction, as above stated, also saves the material where no use of it is now made. I have, therefore, made a superior tie by combining several new features 85 among which are cutting away a part of the back fold of the outer material, fastening the edges of the outer material together by a strip placed above the lining, thus doing 90 away with the ridge on the back fold of the tie, the use of a tab on the small end of the tie and stitching the neck band and a part of the small end of the tie through all 95 the parts thereof.

Having described my invention, what I claim as new and desire to protect by Letters Patent is,

1. A necktie consisting of a neck band portion and end portions, and comprising 100 folded outer material, said outer material overlapping at the back of the tie only at the ends of said end portions, a lining, a strip placed above said lining, and a band, said band being attached over said strip, 105 and being of single thickness throughout.

2. A necktie consisting of a neck band portion and end portions, and comprising

folded outer material, said material overlapping only at the ends of the end portions, a lining, a strip placed between the folds of the folded material and fastened 5 to the back fold thereof, and a band covering said strip and the edges of the back fold of the folded material, said neck por-

tion and part of the narrower end portion being stitched entirely through the tie, and part of the wider end portion being stitched 10 through all the parts of the tie except the front fold of the outer material.

In testimony whereof I affix my signature.
WILLIAM K. MEYER.
